FOUR-CELL COMPARTMENTED CARTON

Homer W. Forrer, Atlanta, Ga., assignor, by mesne assignments, to Mead Packaging, Inc., a corporation of Ohio

Application October 10, 1956, Serial No. 615,197

3 Claims. (Cl. 220—113)

This invention relates to compartmented paperboard 15 cartons of the type adapted for carrying bottles and other similar containers, and more particularly to an improved carton of this sort in which the structure is arranged to employ a blank that may be nested so as to be cut from a web of paperboard with substantially no waste, and in which the structural arrangement provides double thickness partitions at all carton compartments and further incorporates a handle portion integrated with the partition structure.

These and other features of the carton structure provided according to the present invention are described in further detail below in connection with the accompanying drawings, in which:

Fig. 1 is a perspective view of a compartmented carton arranged in accordance with the present invention;

Fig. 2 is a vertical section taken substantially at the line 2—2 in Fig. 1;

Fig. 3 is a further vertical section taken substantially at the line 3—3 in Fig. 2;

Fig. 4 is a plan view of the form of blank used according to the present invention for forming the carton shown in Figs. 1, 2 and 3, with the glue application for the first folding step in forming the carton indicated by stippling, and the nestable arrangement of adjacent blanks indicated in dotted lines;

Fig. 5 is a plan view showing the blank of Fig. 4 after completion of the first folding step in forming the carton;

Fig. 6 is a plan view showing the blank of Fig. 4 after completion of the second folding step in forming the carton, and with the glue application for the third folding step indicated by stippling;

Fig. 7 is a plan view showing the blank of Fig. 4 after completion of the third folding step in forming the carton, and with the glue application for the fourth folding step indicated by stippling;

Fig. 8 is a plan view showing the blank of Fig. 4 after completion of the fourth folding step in forming the carton, and with the glue application for the final folding step indicated by stippling; and

Fig. 9 is a plan view of the completed carton in collapsed position following the final folding step in forming the carton and with the carton ready for erection to the form shown in Fig. 1.

Referring now in detail to the drawings and more particularly at first to Fig. 1, the illustrated carton embodying the present invention is shown as comprising a medial handle portion 10, opposed pairs of end wall panels 12 and 14 foldably joined at the ends of the handle portion 10, opposed side walls 16 and 18 foldably connected between the outer edges of the end wall panel pairs 12 and 14, and a bottom wall panel 20 foldably connected between the bottom edges of the side wall panels 16 and 18, with medial and transverse partition elements arranged as portions of partition extensions (indicated generally by the reference numerals 22, 24, 26 and 28) foldably connected with both the end wall panel pairs 12 and 14 and the side walls 16 and 18

2

and integrated with the handle portion 10, as previously mentioned, to form two compartments along the side walls 16 and 18 at each side of the handle portion 10 with the medial and transverse partitioning for each compartment being provided in double thickness as illustrated further in Figs. 2 and 3. Fig. 3 also illustrates in detail the arrangement of the handle portion 10 as being formed with a first handle panel 30 and a second handle panel 32 foldably joined at their top edges and doubled over the 5 medial partition elements of the partition extensions 28 and 30, with the second handle panel 32 thereof extended downwardly and secured between the paired medial partition elements forming the double thickness medial partitions.

The form of blank by which this structural arrangement is obtained according to the present invention is illustrated in Fig. 4, in which the bottom wall panel 20 is shown arranged at a generally central position in the blank with a medial fold line 34 formed therein to render it collapsible. The side wall panels 16 and 18 are foldably joined along each side edge of the bottom wall panel 20 at fold lines 36 and 38, and one end wall panel of each pair 12 and 14 is foldably joined at the end edges of each side wall panel 16 and 18 along fold lines 40 and 42, and 44 and 46, respectively, the end wall panels of each pair 12 and 14 having a width corresponding to half the width of the bottom wall panel 20 so that these pairs of panels 12 and 14 are proportioned to extend from the side wall panels 16 and 18 and meet medially of the carton at the ends of the handle portion 10 as seen in Fig. 1.

The previously mentioned partition extensions 22, 24, 26 and 28 that are provided to form the compartments in the carton of the present invention are arranged as substantially symmetrical extension panels connected directly with the respective end wall panels of the pairs 12 and 14 at fold lines 22', 24', 26' and 28'. These partition extension panels 22, 24, 26 and 28 are referred to as being symmetrical because they are in substance, each 35 being formed with respective medial and transverse partition portions 48 and 50, 52 and 54, 56 and 58, and 60 and 62, foldably joined at intermediate fold lines 64, 66, 68 and 70. The medial partition portions 48, 52, 56 and 60 are all proportioned with an extent from the respective end wall panels 12 and 14 that is equal to one-half the length of the side wall panels 16 and 18 and at least one of the transverse partition portions, such as 40 54 and 58, of the two partition extensions adjacent each side wall panel 16 and 18 is proportioned with an extent from its related medial partition portions 52 and 56 equal to one-half the width of the bottom wall panel 20, and has an attaching flap 72 or 74, foldably joined along a fold line 76 or 78 at the extending end thereof to provide for securing these transverse partition portions 54 and 58 to the respective side wall panels 16 and 18. The 45 partition extension panels are also specifically different in that the extension panels 24 and 28 have the medial partition portions 52 and 60 thereof formed with locking notches 80 and 82 at their inner or bottom edge for the purpose of locking the medially foldable bottom wall panel 20 in place when the carton is erected as shown in Fig. 2; and the extension panels 26 and 28 are extended at the outer or top edge thereof beyond the outer or top edge of the end wall panels 12 and 14 to which they are joined for the purpose of integration with the medial handle portion 10.

For this latter purpose, the medial partition portion 56 is extended sufficiently to have the first handle panel 30 foldably joined theron along the same fold line 26' at which the medial partition portion 56 is joined to the adjacent end wall panel 12, the first handle panel 30 being hinged in this manner at an end thereof and extending

along the outer or top edge of the adjacent end wall panel 12 and midway of the side wall panel 18 where it remains attached in the blank to the side wall panel 18 at a weakened separation line 84 by which the handle portion 10 is maintained in proper relation to the remainder of the blank during the carton forming steps until ready for separation therefrom as described in further detail below. The second handle panel 32 of the handle portion 10 is foldably joined at the outer or top side of the first panel 30 along a fold line 86 for doubling therewith as previously mentioned. Both of the first and second handle panels 30 and 32 are substantially coextensive in length with the side wall panels 16 and 18 so as to extend for the full length of the carton between the pairs of end wall panels 12 and 14 in the completed carton structure. Also, the second handle panel 32 is formed with a width exceeding that of the first handle panel 30 so that it may be secured between the paired medial partition portions 48 and 56, and 52 and 60, in the completed carton structure, as illustrated in Fig. 3.

The form of blank shown in Fig. 4 should also be noted particularly in connection with the manner in which one of the partition extension panels, such as 26 and 28, joined to each pair of end wall panels 12 and 14, is internestable in inverted relation between the respective partition extension panels 22 and 26, and 24 and 28, joined to the corresponding pair of end wall panels of a like blank, as illustrated by dotted lines in Fig. 4. The internestable partition extension panels 26 and 28 are arranged adjacent the handle portion 10 in the blank of Fig. 4 so that the result of the internesting is to allow the blanks to be cut with substantially no waste from a web of paperboard corresponding in width to the width from top to bottom of the blank in Fig. 4, and thereby effect a very substantial economy in the manufacture of the carton of the present invention.

As to the carton forming steps, it will be seen from Fig. 5 that the partition extensions 22 and 26 are first folded about the fold lines 22' and 26' so as to overlie the inner faces of the adjacent end wall panels 12 and side wall panels 16 and 18, and the partition extension panel 26 is secured at the inner face of the side wall panel 18 by glue previously applied to the attaching flap 74 thereon as indicated in Fig. 4.

Next, the other partition extension panels 24 and 28 are folded about the intermediate fold lines 66 and 70 therein and glue is applied to the exposed faces of the attaching flap 72 on the transverse partition portion 54, and to the exposed faces of transverse partition portion 62 and transverse partition portion 50, as indicated in Fig. 6; after which the end wall panels 14 with the folded partition extension panels 24 and 28 are folded about the side wall fold lines 42 and 46, as seen in Fig. 7, so that securing of the adjacent transverse partition portions in face to face relation is accomplished together with attachment of these partition portions to the side walls 16 and 18 at the attaching flaps 72 and 74.

Then glue is applied at the inside face of the second handle panel 32 along its end edges as indicated in Fig. 7 so that the handle panel 32 may be doubled in relation to the first handle panel 30 to be secured thereto and at the inside faces of the adjacent medial partition portions 56 and 60 as illustrated in Fig. 8; whereupon a glue application is made at the inside faces of the medial partition portions 48 and 52 as indicated in Fig. 8 and a final fold is made about the medial fold line 34 in the bottom wall panel 20 to secure the paired medial partition portions in face to face contact with the lower edge of the second handle panel 32 anchored therebetween to complete the carton of the present invention in collapsed form as seen in Fig. 9 ready for erection to the form illustrated in Fig. 1.

The present invention has been described in detail above for purposes of illustration only and is not intended

to be limited by this description or otherwise except as defined in the appended claims.

- I claim:
1. A compartmented carton of the type adapted for carrying bottles and other similar containers, said carton comprising a medially foldable bottom wall, opposed side walls foldably hinged at the sides of said bottom wall, opposed pairs of end wall panels foldably joined at the ends of said side walls, substantially symmetrical partition extensions foldably joined to each of said end wall panels, and a medial handle portion foldably hinged on one of said partition extensions, said partition extensions each being intermediately foldable into medial partition portions and transverse partition portions, the medial partition portion of the partition extension on which said medial handle portion is hinged being extended in height across the entire width thereof above the adjacent end wall and having said medial handle portion hinged thereon along the same axis at which said medial partition portion is hinged on said adjacent end wall, the medial partition portion that is foldably joined to the end wall panel on the same side wall also being extended in height across the entire width thereof above the end wall panel adjacent thereto, and said medial handle portion including a first handle panel foldably hinged at an end thereof on said medial partition portion that is extended in height therefor and a second handle panel foldably joined at the top edge of said first handle panel and having the opposite side edge and both end edges thereof free, both of said handle panels being substantially coextensive in length with said side walls and being doubled over the extended height of said medial partition portions that are extended above said end wall panels and secured thereto.
  2. A compartmented carton of the type adapted for carrying bottles and other similar containers, said carton comprising a medially foldable bottom wall, opposed side walls foldably hinged at the sides of said bottom wall, opposed pairs of end wall panels foldably joined at the ends of said side walls, substantially symmetrical partition extensions foldably joined to each of said end wall panels, and a medial handle portion foldably hinged on one of said partition extensions, said partition extensions each being intermediately foldable into medial partition portions having an extent from said end wall panels equal to one-half the length of said side walls and into transverse partition portions of which at least one of the two extensions adjacent each side wall has an extent from said medial partition portions equal to one-half the width of said bottom wall and is secured to said adjacent side wall, the medial partition portions extending from each pair of end wall panels and the transverse partition portions adjacent each side wall being secured in face to face relation, the medial partition portion of the partition extension on which said medial handle portion is hinged being extended in height across the entire width thereof above the adjacent end wall and having said medial handle portion hinged thereon along the same axis at which said medial partition portion is hinged on said adjacent end wall, the medial partition portion that is foldably joined to the end wall panel on the same side wall also being extended in height across the entire width thereof above the end wall panel adjacent thereto, and said medial handle portion including a first handle panel foldably hinged at an end thereof on said medial partition portion that is extended in height therefor and a second handle panel foldably joined at the top edge of said first handle panel and having the opposite side edge and both end edges thereof free, both of said handle panels being substantially coextensive in length with said side walls and being doubled over the extended height of said medial partition portions that are extended above said end wall panels and secured thereto, and said second handle panel extending downwardly below said first handle panel and being further secured between the medial partition portions extending from each pair of end wall panels.

3. A blank of paperboard or the like for forming a collapsible compartmented carton, said blank being cut and scored to define a medially foldable bottom wall panel, opposed rectangular side wall panels foldably joined at the sides of said bottom wall panel, opposed pairs of rectangular end wall panels foldably joined co-extensively at the ends of said side wall panels, and substantially symmetrical partition extension panels foldably joined to the extending edge of each of said end wall panels, said partition extension panels each being intermediately foldable into medial partition portions having an extent from said end wall panels equal to one-half the length of said side wall panels and into transverse partition portions of which at least one of the two extensions adjacent each side wall panel has an extent from said medial partition portions equal to one-half the width of said bottom wall panel and has an attaching flap at the extending edge thereof for securing to said adjacent side wall panel, and the medial partition portion of one of said partition extension panels being extended beyond the outer edge of the end wall panel to which it is joined and having a first medial handle panel foldably hinged thereon and extending along the outer edge of said end wall panel and the adjacent side wall panel, and a second medial handle panel foldably joined at the outer side of

said first handle panel for doubling therewith, both of said handle panels being substantially coextensive in length with said side wall panels and said second handle panel having a width exceeding that of said first handle panel, and the medial partition portion of the partition extension panel that is foldably joined to the end wall panel on the same side wall with the end wall panel adjacent which said first handle panel is foldably joined being likewise extended beyond the outer edge of the end wall panel adjacent thereto, whereby said handle panels are adapted to be doubled over said extended medial partition portions and said wider second handle panel is adapted to be disposed between the respective medial partition portions paired with said pairs of end wall panels.
